UNITED STATES PATENT OFFICE

96,433

DESIGN FOR A CHARM OR SIMILAR ARTICLE OF JEWELRY

Felix B. Vollman, Rockaway Park, N. Y.

Original application February 1, 1935, Serial No.
55,189. Divided and this application March 23,
1935, Serial No. 56,027

Term of patent 14 years

To all whom it may concern:

Be it known that I, Felix B. Vollman, a citizen of the United States and a resident of Rockaway Park, in the county of Queens and State of New York, have invented a new, original, and ornamental Design for a Charm or Similar Article of Jewelry, as shown, of which the following is a specification, reference being had to the accompanying drawing, forming a part hereof.

Figure 1 is a plan view of the charm or similar article of jewelry showing my new design, the material being formed from precious or semi-precious metals or similar materials;

Figure 2 is an end elevation thereof.

This application is a division of my prior filed application Serial No. D-55,189, filed February 1, 1935.

I claim:

The ornamental design for a charm or similar article of jewelry, as shown and described.

FELIX B. VOLLMAN.
